UNITED STATES PATENT OFFICE

157,682

THERMOSTATIC CONTROL OR SIMILAR
ARTICLE

Richard E. James, Pasadena, and William A. Pentecost, South Pasadena, Calif., assignors to Rheem Manufacturing Company, Richmond, Calif., a corporation of California

Application October 4, 1948, Serial No. 148,956

Term of patent 14 years

(Cl. D81—2)

To all whom it may concern:

Be it known that we, Richard E. James and William A. Pentecost, citizens of the United States, residing in Pasadena and South Pasadena, respectively, in the county of Los Angeles, State of California, have invented a new, original, and ornamental Design for a Thermostatic Control or Similar Article, of which the following is a specification, reference being had to the accompanying drawings, forming a part thereof.

Figure 1 is a front elevational view of a thermostatic control embodying our new design.

Figure 2 is a side view taken from the left of Figure 1.

Figure 3 is a side view taken from the right of Figure 1.

Figure 4 is a top plan view.

Figure 5 is a bottom plan view thereof.

We claim:

The ornamental design for a thermostatic control or similar article, as shown.

RICHARD E. JAMES.

WILLIAM A. PENTECOST.
